CLAIM

The ornamental design for a non-metallic seal for an underwater luminaire, as shown and described.

DESCRIPTION

FIG. 1 is a perspective view of a non-metallic seal from the front end, showing my new design;

FIG. 2 is a left side view thereof, the right side being a mirror image thereof, and the top and bottom views being identical thereto;

FIG. 3 is a front elevational view thereof;

FIG. 4 is a rear elevational view thereof; and,

FIG. 5 is a perspective view of a non-metallic seal from the rear end.
